Related U.S. Application Data

(62) Division of application No. 29/486,565, filed on Mar. 31, 2014.

CLAIM

The ornamental design for palmless glove, as shown and described.

(51) **LOC (10) Cl.** **02-06**

DESCRIPTION

(52) **U.S. Cl.**

FIG. 1 is a perspective view of the palmless glove embodying the new design;

USPC **D29/116.3**

FIG. 2 is a front view thereof;

(58) **Field of Classification Search**

FIG. 3 is a rear view thereof;

None

FIG. 4 is a left side view thereof;

See application file for complete search history.

FIG. 5 is a right side view thereof;

(56) **References Cited**

FIG. 6 is a top view thereof;

U.S. PATENT DOCUMENTS

FIG. 7 is a bottom view thereof, with finger portions visible through an open aperture of the palmless glove; and,

(Continued)

FIG. 8 is a cross section of the palmless glove taken along lines 8-8 of FIG. 2.

FIGS. 1-8 show features of a palmless glove in broken lines. The features shown in long-short-short-long dashed lines illustrate portions of the palmless glove that form no part of the claimed design. The long-short-short-long dashed lines immediately adjacent to the solid-line portions of the design form the bounds of the claim and form no part of the claimed design. The short-short dashed lines represent conventional stitching and form no part of the claimed design. The stipple shaded portions of the palmless glove are claimed.
